UNITED STATES PATENT OFFICE.

MALCOLM P. FERGUSON, OF ELMIRA HEIGHTS, NEW YORK, ASSIGNOR TO ECLIPSE MACHINE COMPANY, OF ELMIRA, NEW YORK, A CORPORATION OF NEW YORK.

ENGINE STARTER.

Application filed November 15, 1923. Serial No. 674,898.

My invention relates to engine starters for the starting of an engine such as an internal combustion engine, and more particularly to that part of such a system known as the 5 drive or transmission which transmits the power of a prime mover such as an electric motor to a member of the engine to be started such as the flywheel thereof.

In the present embodiment of my invention, a driving member such as a pinion is 10 adapted to be manually meshed with the flywheel and to be automatically disengaged therefrom when the engine operates on its own power. This pinion is adapted to be 15 subjected to a yielding pressure such as spring pressure and the object of my invention is to provide for the pinion a pressure afforded by a novel construction and arrangement of a spring so that the spring 20 pressure shall be variable according to the different positions of the pinion in the different phases of operation in the cycle of operation of the drive.

In the drawing, Fig. 1 is a sectional elevation of a starting system embodying my invention illustrating the relative position of the parts in disengaged position by full lines and cranking or engaged position by dotted lines; Fig. 2 a detail sectional elevation similar to Fig. 1 but illustrating the catch device in section and in inoperative position; Fig. 3 a view similar to Fig. 2 but with the pinion demeshed and caught by said device; and Fig. 4 a section on the line 4—4 of Fig. 1.

For the sake of a clear and definite description of my invention, I have shown the same incorporated in a drive of the outboard and direct drive type, but it will be understood that such invention is also applicable 40 to the inboard and indirect type of drive.

Referring to the particular embodiment of my invention as shown, the prime mover is here an electric motor 1 having an extended armature shaft 2 provided at its outer end 45 with a suitable bearing 3 in a casing or bracket 4 which is secured in a suitable manner to the motor frame. A hollow shaft or sleeve 5 is mounted upon the driving or armature shaft for longitudinal movement thereof and rotary movement therewith through the medium of longitudinal splines

5 on the armature shaft which are engaged by the splined bore of the hollow shaft. This latter shaft is provided with screw threads 7 and may, therefore, be called a 55 screw shaft and the same is provided at its inner end as a separate or integral part thereof with parallel flanges 8 forming between them a circumferential groove 9. With this groove there cooperates a roller 60 10 of the shifting means which may be of any suitable character, but which as shown is a lever 11 pivoted at 12 in the casing 4 and actuated by the operator by hand or foot. 65

The driving member is here in the form of the pinion 13 which is threaded upon the screw shaft for longitudinal movement thereof into engagement with the teeth of the flywheel 14 and for rotary movement with such 70 screw shaft. This pinion is normally held spring pressed against a stop nut 15 at the outer end of the screw shaft. The spring means for this purpose, now about to be described, cooperates with the pinion and in 75 the present instance is in contact therewith and the same also serves to return the pinion to normal position against the stop nut after being automatically demeshed from the flywheel. The object of my invention is to provide a novel and efficient spring means which 80 shall perform these functions and at the same time not interfere with the freedom of movement of the pinion during its demeshing operation. 85

To this end, I provide a spiral spring 16 of suitable tension and length and interpose it between the inwardly projecting annular rib or abutment 17 in the casing 4 and the pinion 13, there preferably being a spring 90 abutment or plate 18 carried by the pinion to receive the outer end of this spring.

My drive also includes means for catching and holding the pinion in retracted position on the screw shaft after being demeshed 95 from the flywheel, thereby preventing the pinion from contacting the flywheel in case the screw shaft should be left in shifted position after the engine has been started. Such means, which are shown in Figs. 2 and 3, 100 comprise a latch 19 pivoted in a longitudinal slot 20 in the screw shaft and adapted to en-

gage a notch 21 in the bore of the pinion. Normally the outer end of the latch lies in a groove between two of the splines 6 of the armature shaft and the inner end bears 5 against the periphery of such armature shaft. When the screw shaft is shifted to the left the inner end of the latch will ride down the slope 22 at the inner end of such groove by reason of the pressure of the spring 23 located 10 within the drum 24, with the result that the outer end of the latch will be moved radially to operative position to engage the notch 21 when the pinion is within the range of the latch. Upon demeshing, the pinion 15 moves longitudinally inwardly on the screw shaft and is caught by the latch as shown in Fig. 3, and thereby prevented from returning to normal position until the latch is actuated to release it in the manner hereinafter 20 explained.

The size and length of the spring 16 are such that when the drive is in the normal position shown in full lines in Fig. 1, the spring is under some compression and holds the 25 pinion in normal position against its stop nut 15. However, when the drive assembly is shifted longitudinally to the left with the pinion in mesh with the flywheel as shown in dotted lines, the spring will expand to its 30 full extent and the same contacts with the pinion with practically no pressure. Consequently when the pinion is demeshed in the well known automatic manner, there is comparatively little resistance to its demeshing 35 movement. When the pinion, in such demeshing movement, comes within the range of the latch it is caught and retained thereby as shown in Fig. 3. At this time the spring 16 is compressed to its maximum and 40 exerts its full pressure upon the pinion. When the screw sleeve is returned to normal position the latch is operated and the pinion is released in the manner above explained, and the spring is permitted to exert such 45 maximum pressure upon the pinion to forcibly return it to its normal position against the stop nut, the lead of the screw threads being such as to permit of this return.

I do not herein broadly claim the construction and the arrangement of the drive including the longitudinally shiftable sleeve or driving member or pinion thereon and the catch device for holding the pinion in demeshed position while the screw shaft or 55 sleeve is still shifted to cranking position as the same represent subject matter of prior applications filed by William L. McGrath including an application filed by him on January 4, 1923, Serial No. 610,672, the present application being directed to the particular invention pointed out in the claims herein.

I claim:

1. An engine starter drive including a rotatable longitudinally movable shaft, a driv-

ing member mounted thereon for rotary movement therewith and for longitudinal movement therewith and thereon, and a spring mounted independently of the drive and arranged in the path of longitudinal movement of the driving member to hold it in normal position and to return it to that position after such driving member has compressed it in the longitudinal disengaging movement of the driving member on the 75 shaft.

2. An engine starter drive including a rotatable longitudinally movable shaft, a driving member mounted thereon for rotary movement therewith and for longitudinal 80 movement therewith and thereon, and a spring mounted independently of the drive and arranged in the path of longitudinal movement of the driving member to hold it in normal position and to return it to that 85 position after such driving member has compressed it in the longitudinal disengaging movement of the driving member on the shaft, said spring having one end free and adapted to be contacted by the driving mem- 90 ber.

3. An engine starter drive including a longitudinally movable rotatable shaft, a driving member mounted thereon for rotary movement therewith and for longitudinal 95 movement therewith and thereon, and a spring mounted independently of the drive and arranged in the path of longitudinal movement of the driving member to hold it in normal position and to return it to that position after such driving member has compressed it in the longitudinal movement of the driving member on the shaft, said spring being a spiral spring with its smaller end 100 free and adapted to be contacted by the driving member.

4. An engine starter drive including a longitudinally movable rotatable shaft, a driving member mounted thereon for rotary movement therewith and for longitudinal 110 movement therewith, a casing surrounding the drive and having an interior circular rib, and a spiral spring whose larger end abuts the rib and whose smaller end is arranged in the path of movement of the driving member.

5. An engine starter drive including a longitudinally movable shaft with long lead screw threads, a pinion threaded thereon for rotary movement therewith and for longitudinal movement therewith, a stop on the shaft, and a spring mounted independently of the drive and arranged in the path of longitudinal movement of the pinion to hold it in normal position against the stop and to return it to that position after such driving member has compressed it in the longitudinal disengaging movement of the driving member on the shaft.

6. An engine starter drive including a ro-

tatable driving shaft, a sleeve mounted to slide longitudinally thereon and to be driven thereby, a driving member mounted on the sleeve for rotary movement therewith and for longitudinal movement therewith and thereon and a spring mounted independently of the drive and arranged in the path of longitudinal movement of the driving member to hold it in normal position and to return it to that position after such driving member has compressed it in the longitudinal disengaging movement of the driving member on the shaft. 10
